UNITED STATES PATENT OFFICE.

VIRGINIA H. PENDLETON, OF NEW YORK, N. Y.

DESIGN FOR A CARRYING BAG.

Application filed May 11, 1922. Serial No. 2,196. Term of patent 7 years.

To all whom it may concern:

Be it known that I, VIRGINIA H. PENDLETON, a citizen of the United States of America, and a resident of the city of New York, in the borough of Manhattan and county of New York and State of New York, have invented a new, original, and ornamental Design for a Carrying Bag, of which the following is a specification, reference being had to the accompanying drawing, forming part thereof.

I claim:

The ornamental design for a carrying bag as shown.

VIRGINIA H. PENDLETON.

Witnesses:

GILBERTA D. GOODWIN,
SAMUEL W. BALCH.
